His Atty.

UNITED STATES PATENT OFFICE.

CHARLES H. CHAPMAN, OF SHIRLEY, ASSIGNOR TO THE STANDARD SPINDLE COMPANY, OF AYER, MASSACHUSETTS.

SPINDLE AND MEANS FOR SUPPORTING THE SAME.

SPECIFICATION forming part of Letters Patent No. 244,712, dated July 19, 1881.

Application filed September 27, 1880. (No model.)

To all whom it may concern:

Be it known that I, CHARLES H. CHAPMAN, of Shirley, in the county of Middlesex and State of Massachusetts, have invented certain 5 Improvements in Spindles and Means for Supporting the Same, of which the following is a specification.

The invention consists in a standard for a shell-spindle fitted loosely and adapted to vibrate in its step or support, so that when the spindle is rotated the standard and spindle will be centered or held steadily in a vertical position by centripetal force, all of which I will now proceed to describe and claim.

15 The accompanying drawing, forming a part of this specification, represents a vertical central section of a spindle having a loose step.

I have found in a shell-spindle supported by a standard, that if the standard is allowed 20 to have some lateral play in its base or support the spindle will run more steadily than when the standard is rigid.

I have shown a spindle having a standard, S, which is inserted in a base, T, having a 25 socket of sufficient size to receive the standard and permit it to play laterally.

To secure the standard in the base so that it will not rotate with the spindle nor be pulled out when the bobbin is doffed I drill a hole, 30 U, in the standard, insert a pin, V, in the hole, and then force the standard down into its base, the pin being of such length that its ends will bind tightly against the interior of the socket

and prevent the withdrawal of the standard. The hole U is of such size that it will permit 35 the lateral play of the standard.

When the spindle is rotated on the standard the centripetal force centers it and keeps it steadily in a vertical position, the principle being the same as that of the well-known toy 40 known as the "top."

C represents the live spindle, having a tapered whirl, D, and a pin, P, on the rail, to prevent the slipping off of the band from the whirl.

What I claim is—

1. The combination of a spindle, C, its standard S, and a socketed base, T, to receive said standard, the said standard being of considerably less diameter than the socket, so as to 50 fit loosely and vibrate therein, whereby as the spindle is rotated the standard and spindle will be centered or held steadily in a vertical position, substantially as shown and described.

2. The spindle, a standard therefor, and a 55 socketed base in which said standard is loosely fitted and adapted to vibrate, in combination with a pivot-pin, substantially as shown and described.

In testimony whereof I have signed my 60 name to this specification in the presence of two subscribing witnesses.

CHARLES H. CHAPMAN.
